UNITED STATES PATENT OFFICE.

WADE HAMPTON SMITH, OF MACON, GEORGIA.

COVER FASTENING AND RELEASING DEVICE.

1,029,405.

Specification of Letters Patent. Patented June 11, 1912.

Application filed February 8, 1912. Serial No. 676,475.

To all whom it may concern:

Be it known that I, WADE HAMPTON SMITH, a citizen of the United States, residing at Macon, in the county of Bibb and 5 State of Georgia, have invented certain new and useful Improvements in Cover Fastening and Releasing Devices, of which the following is a specification.

The primary object of this invention is to 10 provide novel means for coöperation with a receptacle and the locking means therefor for releasing said locking means and successively raise the cover of said receptacle.

My invention is capable of application to 15 various and numerous characters of receptacles and I do not wish to be confined to the particular form illustrated in the accompanying drawings.

For a full understanding of the present 20 invention, reference is to be had to the following description and the accompanying drawings, in which—

Figure 1 is a bottom plan view of a receptacle cover provided with the preferred 25 form of locking means; Fig. 2 is a longitudinal sectional view showing a receptacle as applied for use in connection with water meters, showing the cover locked in engagement with said receptacle; Fig. 3 is a view 30 in elevation similar to Fig. 2, the receptacle being broken away to more clearly show the operation of the means for releasing the lock of the receptacle and raising the cover. Fig. 4 is a detail view of the rock shaft used 35 with my device, and Fig. 5 is a partial view of the key lever for releasing the lock and raising the cover of the receptacle.

Throughout the following detail description and on the several figures of the drawings, similar parts are referred to by like 40 reference characters.

In carrying out my invention, a construction embodying the same comprises a receptacle 1 having a cover 2 seated thereon. 45 At one end of the under side of the cover is formed a locking lug 3 adapted to interlock with a projection 4 on one end of the receptacle 1. At the end opposite the lug 3 is mounted for pivotal movement a rock shaft 5 having its bearings in the spaced 50 eyes 6 carried by the cover 2. The opposite ends of said rock shaft 5 are bent downwardly to form the movable locking catches 7 adapted to be engaged with the locking 55 lugs 8 carried by the end of the receptacle 1. It will be apparent that a cover provided

with the locking means aforesaid is applied to the receptacle by placing the end having the locking lug 3 on the receptacle and by lowering the opposite end, the normally depending catches 7 will automatically engage with the lugs 8 to lock the cover in position on said receptacle.

As is most clearly shown in Fig. 4 of the drawings, the rock shaft 5 is reduced at its 60 central portion as indicated at 5' and the cover 2 is formed with an open end slot 2' just above the reduced portion 5'.

To gain access to the contents of the receptacle a novel form of key lever is employed and designated in the drawings by the numeral 9. One end of the lever 9 is formed with a hook 10 and said lever is inserted through the slot 2' of the cover and engaged over the reduced portion 5' of the 65 rock shaft 5. With a side of the receptacle 1 as a fulcrum, a slight downward movement on the lever 9 will disengage the catches 7 from the lugs 8 to release the locking means of the cover and by a further 70 downward movement of the lever, said cover is raised a desired amount to permit of its removal from the receptacle.

In Fig. 2 of the drawings I have shown the receptacle as applied for use in connection with a water meter 11 but it will be obvious that the construction is equally applicable to service boxes, man-hole covers or 75 similar receptacles.

Having thus described the invention, what 80 is claimed as new is:

1. In combination, a receptacle, a cover therefor, locking means coöperating with said cover to hold the same closed with respect to the receptacle, and a lever adapted 85 to be engaged with said locking means to release the same and upon continuous movement to raise the cover aforesaid.

2. In combination, a receptacle, a cover therefor, means including catches pivotally 90 mounted on said cover and adapted to automatically engage the receptacle to lock the same closed, and a lever adapted to be engaged with said means to release the catches and upon continuous movement to raise the 95 cover.

3. In combination, a receptacle comprising locking projections, a cover therefor, a rock shaft pivotally mounted on said cover and having normally depending locking 100 catches for interlocking with the projections aforesaid, said shaft having a reduced por-

tion intermediate its ends, the cover aforesaid having a slot adjacent the reduced portion of the rock shaft, and a key lever adapted to be inserted in the slot in the cover, and formed with a hook to engage the reduced portion of said rock shaft whereby the catches may be disengaged from the locking projections upon movement of the lever and the cover raised by a further movement of said lever.

10 4. In combination a receptacle, a cover therefor, locking means cooperating with the cover to hold the same closed with re-

spect to the receptacle, and a lever engageable with the locking means and adapted to 15 fulcrum on the receptacle whereby on initial movement of said lever the locking means will be released and subsequent movement of the lever will raise the cover.

In testimony whereof I affix my signature 20 in presence of two witnesses.

WADE HAMPTON SMITH.
